DESIGN FOR A PENDANT OR THE LIKE

Abram Blume, Asbury Park, N. J.

Application September 27, 1933, Serial No. 49,358

Term of patent 7 years

To all whom it may concern:

Be it known that I, ABRAM BLUME, a citizen of the United States of America, residing at Asbury Park, in the county of Monmouth and State of New Jersey, have invented a new, original, and ornamental Design for a Pendant or the like, of which the following is a specification, reference being had to the accompanying drawing, forming part thereof.

I claim:

The ornamental design for a pendant or the like, as shown.

ABRAM BLUME.
